PASSENGER SEAT

Leonard Ralph Sorge, Westport, Conn., assignor to United Aircraft Corporation, East Hartford, Conn., a corporation of Delaware

Filed Mar. 14, 1960, Ser. No. 59,719

Term of patent 14 years

(Cl. D15—8)

FIG. 1

FIG. 2

Fig. 1 is a side elevational view of a seat, showing my new design; and

Fig. 2 is a front elevational view.

The passenger seat shown has a back of conventional configuration.

I claim:

The ornamental design for a passenger seat, substantially as shown and described.
